GUNNERY PRACTICE RANGE CONTROL
DEVICE

Clarence W. Clarkson, Jr., Corning, N. Y.

Application December 27, 1945, Serial No. 637,474

6 Claims. (Cl. 35—25)

(Granted under the act of March 3, 1883, as
amended April 30, 1928; 370 O. G. 757)

1

The invention described herein may be manufactured and used by or for the Government for governmental purposes without payment to me of any royalty thereon.

This invention relates to improvements in control devices for aircraft gunnery practice ranges, and more particularly to control devices for effecting an automatic operational control of the aircraft gunnery range apparatus.

These gunnery practice ranges each include a platform mounted for rotation about a fixed axis, or the axis of the platform may be mounted for tilting movements in a vertical plane, in addition to the aforesaid rotative movements.

The platform simulates the body of an aircraft, such as a bomber, and has a directional gun unit, or a complete aircraft gun turret mounted thereon, the gun unit or turret being capable of rotation with the platform, and independent rotation under the control of a gunner within the turret, incident to the training of the gun unit or turret on a sighting target. Rotation of the platform, and tilting thereof, if the tilting provision is incorporated, is by suitable power drive means under the control of a gunnery instructor or other operator in an instructor's station, preferably located at one side of the platform beyond the confines thereof.

The sighting target is preferably in the form of a miniature target airplane depending from a carriage that travels on a track frame inclined above the line of fire from the guns when trained in a substantially horizontal position, with the line of travel of the sighting target parallel to the track frame in a vertical plane, preferably toward the axis of rotation of the turret and in the plane of the gun sighting means when the guns are horizontal. Power means is provided for moving this sighting target toward the turret. Manually adjustable control means is also provided at the aforesaid instructor's station for controlling the movement of this sighting target along the track, independently of turret or platform rotation.

In completing this brief description of this known gunnery practice range, a scoring means is provided for determining the accuracy of the gunners' sighting operations. This preferably comprises a stationary scoring target having scoring "bull's eyes" thereon, one for each of the guns, when a multiple control unit is employed. These scoring targets may be spaced apart laterally so that each "bull's eye" is centered in the line of fire of one of the guns which is carried by the turret, or gun unit, and this scoring target is located below the inclined plane of movement of

the sighting target so that "live" ammunition in the guns can be used to register on the scoring target without striking the sighting target.

Assuming that a gunner is aiming the guns, having conventional gun sights thereon that have been previously adjusted to the plane of movement of the sighting target while the guns were bore-sighted on the scoring target, proper sighting of the guns and firing thereof will score on the "bulls' eyes" regardless of any rotational or tilting movements of the supporting platform.

Rotation of the platform, however, during the movement of the sighting target toward the gunner, when observed through the gunsight means, simulates a compound forward and lateral movement of the sighting target toward the gunner. This produces the effect of a pursuit plane flying toward the gunner as he sights the guns on the sighting target, his position being that of a gunner in an aircraft, such as a bomber, in flight. Relative changes in the rates of rotation of the platform and speed of travel of the sighting target toward the gunner simulates different, definite, pursuit curves such as would be flown by the pursuit plane, when attacking the bomber from different angles.

The instructor, manipulating the platform and sighting target controls, may vary or adjust the respective power means for the platform and sighting target to move the sighting target and rotate the platform at any desired relative ratios.

My improvement comprises means for automatically predetermining the respective rates of movements of the platform and the sighting target plane, in order to simulate with precision, a predetermined number of different, definite, pursuit curves being flown by an attacking pursuit plane, representative of attacks on a bomber from different angles, and while my disclosure incorporates certain details of construction relating to the platform, the sighting and scoring target structures, no claim is made herein to any novelty contained in these specific elements, my invention being in the control means for effecting the individual and relative movements of the respective elements automatically with precision so that an inexperienced operator at the instructor's control station may, by the manipulation of certain control switches, operate the apparatus to simulate a plurality of definite pursuit plane attacks for various angles of approach, thereby making it possible to afford all gunnery candidates an equal or uniform test, relative to his skill in manipulating the turret and aiming and firing the guns.

An object of the present invention, therefore,

is the provision of control means for rotating the platform at a plurality of predetermined different rates, and for moving the sighting target toward the gunner at a plurality of predetermined different rates.

A further object is the provision of a plurality of platform rotation control devices, each of which rotates the platform at a predetermined different speed and control means for selectively connecting any of said control devices to the platform for determining the rate of rotation thereof.

A further object is the provision of a plurality of platform rotational control devices, each being operable to rotate the platform at a different predetermined rate, together with a second group of sighting target control devices, each being operable to cause movement of the sighting target toward the platform at a different predetermined rate, and means for simultaneously connecting a predetermined pair of said platform and sighting target control devices, respectively, to the platform and sighting target power operating means for predetermining the relative rates of movements of the platform and the sighting target.

A further object is the provision of a plurality of individually selectable control devices, located at the instructor's station for simultaneously causing rotation of the platform and movement of the sighting target toward the platform at definite predetermined ratios for simulating the relative movements between a bomber, and a pursuit plane when attacking a bomber from different predetermined angles with respect to the longitudinal axis of the bomber.

Other objects and advantages of this invention will become apparent from the following description, taken in connection with the accompanying drawings, in which like reference characters refer to like parts in the several figures.

Fig. 1 is a somewhat diagrammatical perspective view of an exemplary form of aircraft gunnery range practice range, illustrating my improved control apparatus applied thereto, and located at the instructor's control station, the improved control device being shown in elevation.

Fig. 2 is a fragmentary plan view of a portion of the interior of my improved control device, as illustrated in Fig. 1, disclosing several sets of the platform and sighting target movement control elements and the common timing motor drive means therefor.

Fig. 3 is a fragmentary view in elevation, of one pair of the control devices, as seen in Fig. 2, and its associated switch devices for initiating the aforesaid control devices into operation.

Fig. 4 is a vertical sectional view, taken approximately on the plane indicated by the line 4-4 in Fig. 2, illustrating one of the switch devices, and one of the adjustable control devices with its associated operating cams.

Fig. 5 is a schematic wiring diagram of my improved automatic control system.

Referring to Fig. 1, the aircraft gunnery range practice apparatus comprises a gunner's firing station A, a sight target unit B, a scoring target unit C, and an instructor's control station D. A fixed base 1 is provided, or the base 1 may be tiltable about a horizontal pivot if changes in elevation between the pursuit plane and the bomber are to be simulated. The base 1 carries a supporting platform 2 which is rotatable thereon about a fixed axis, by power means such as a motor 3 which drives a gear train 4, meshing with a ring gear 5 disposed around the platform.

A directable gun unit is mounted on the platform 2, for independent rotation about the turning axis of the platform. This unit may be a complete aircraft gun turret and supporting base structure, as illustrated at 6, with the turret 7 carrying the guns 8, and rotatable on the turret base with the guns 8 adjustable in elevation. A motor 9 is fixed on the platform 2, and carries a worm 10 which meshes with a large worm gear 10a secured to a vertical shaft 10b rotatably journaled on the vertical axis of the platform. A gun mounting bracket is fixed to this shaft 10b and pivotally carries the guns 8, for adjustments in elevation. The turret is connected for rotation with the shaft 10b and carries a control handle for power rotation of the shaft and turret in azimuth, the handle operating a slider contact 11a to vary the effective electrical power from a battery 11b for rotating the turret, through resistance 11c, and the conductors 11d and 11e, connected to the conventional poles of the reversible motor 9, the conductor 11f completing the circuit between the motor 9 and the battery 11b.

With the adjustable contact 11a in mid-position as shown, the two effective portions of the resistance 11c are equal and the potential to the opposing fields of the motor 9, through the conductors 11d and 11e, is equal, preventing rotation of the gun standard or post 10b carrying the guns, and the turret head secured to the post. Movement of the handle up and down varies the two portions of the resistance 11c at the opposite sides of the slider contact 11a, controlling the direction and the rate of rotation of the guns 8 and the turret in azimuth. Limit switches 11g and 11h break the connections 11d and 11e to the motor 9 when the turret and guns are swung too far in azimuth off of the scoring target.

The guns 8 are elevated and depressed electrically, by power means under the control of the gunner, in a similar manner. A reversible motor 12 is fixed to the turret structure, and may be carried by the central standard or post 10b for the guns. The opposing fields of motor 12 are connected by conductors 12a and 12b to a resistance bridge 12c, which is engaged by a slider contact 12d, connected to one terminal of the power source or battery 11b, while the other battery terminal is connected by a conductor 12e to the center pole or common return for the motor 12. Movement of the slider contact 12d up or down, by a gunner within the turret, causes the motor 12 to rotate in one direction or the other, rotating a worm 13 which meshes with a worm segment 13a, secured to the tiltable gun mount, causing the guns to be elevated or depressed as desired. The two slider contacts 12d and 11a, therefore, control the training of the guns 8, independently of any rotational movement of the supporting platform 2 by the instructor or operator in the instructor's station D.

The stationary scoring target C is mounted on suitable supports 17 and carries two "bulls' eyes" 18, preferably located in a vertical plane at right angles to the line of fire of the guns 8 when trained horizontally. The spacing between the "bulls' eyes" is such that the line of fire from each gun will register in the center of each target when the guns are properly trained on the scoring targets. The stationary scoring target C is located at any suitable distance from the guns, depending on the size of

scoring targets employed, the distance being preferably about 1,000 inches.

The sighting target B, employed in the gunnery practice range, comprises a rigid frame 19, having an endless carriage guide track 20 on which a carriage is mounted. The carriage is driven by a flexible member such as a cable 23, trained around a pair of idler pulleys 24 and 25 and a third driving pulley 26. The driving pulley 26 is driven by a gear 27, meshing with a gear 28 that is fixed on the drive shaft of a reversible motor 29. The direction of rotation of the motor and its speed is controlled at the instructor's control station D.

The sighting target frame 19 is laterally adjustable above, and in front of the turret, when the guns are trained on the scoring target C, suitable adjustable supporting means being provided such as indicated at 30, having their lower ends fixed to the sighting frame and their upper ends adjustably secured in the arcuately slotted supports 31.

The sighting means for the guns within the turret may be of any conventional type, either an optical gun sight, or an open gun sight as shown, comprising a front bead 15 and a rear multiple ring or "rad" sight 16, with the sighting axis elevated above the scoring target, when the guns are trained on the "bulls' eyes" thereof. The sighting frame carriage track is positioned in a parallel plane elevated above the sighting plane. A sighting target 32, in the form of a miniature airplane, is dependingly carried on a light rod 33, secured to the carriage 21. The inclined path of movement of the sighting target airplane 32 is located in the sighting axis of the gun sight, when the guns are trained on the scoring target C, and the sighting airplane or target 32 is positioned so that the travel thereof is also in a vertical plane passing through the sighting axis of the sighting means, with the guns trained in azimuth on the scoring target, although to simulate actual conditions, where a certain amount of "lead" is to be calculated by the gunner, as when using special "rad" sights, the sighting frame 19 may be adjusted laterally, to dispose the reach of the guide track on which the carriage travels toward the turret, at one side of the turret and platform turning axis. The aforementioned structure comprises a typical aircraft gunnery practice range to which my improved control apparatus is applied. In the aforementioned typical arrangement two control knobs 34 and 35 are provided at the control station D, for controlling the respective speed ratios of the sighting target motor 29, and the rate of turret rotation by its motor.

In order to properly simulate any sighting problem, at least three variable factors must be taken into consideration, assuming that the aircraft which is simulated by the platform is traveling on a straight course. The first is the speed of the aircraft carrying the gunner, represented by the supporting platform 2; second, the speed of the approaching pursuit plane which is represented by the movement of the sighting target plane 32 toward the axis of the platform; and third, the direction of attack with respect to the longitudinal axis of the bomber carrying the guns, as represented by the platform. From the above it will be noted that it requires an experienced instructor to manipulate the two control knobs 34 and 35 to properly control the turret and sighting target movements to correctly

simulate, due to the compound platform and sighting target movements, the proper pursuit curve flown by the attacking plane. It is doubtful that even an experienced instructor could identically control the relative movements of the platform and sight target for a great number of successive similar tests or problems, and therefore, he could not afford equal and uniform tests to all candidates that are being tested.

- 10 The speeds of the two motors 3 and 29 were formerly controlled by two potentiometers, the relative adjustment of which, during the gunnery practice, determined the relative acceleration and speeds of the platform and sighting target, 15 simulating an attack of an enemy pursuit plane flying different pursuit curves from different attack angles toward the gunner within the turret of a bomber.
- 20 In my improved control system the aforesaid manual control is also included, with switch means for disconnecting the manual control when my improved automatic control is initiated. Referring now to the wiring diagram in Fig. 5, diagrammatically illustrating my control system, 25 the sight target motor 29 and platform motor 3 are of conventional types, designed to operate at different predetermined speeds, depending upon the amount of current supplied to them, and commonly known in the trade as the "amplidyne" 30 type of drive consisting of the usual motor-generator sets 29a 29b, and 3a, 3b, where the motors 29b and 3b are connected to any separate power source not shown, the generator 29a having a generator field 29c connected through the conductors 55 and 57 to the manual control potentiometer device 51, or through the switch device 43 to the automatic control potentiometers 63. The generator field 3c of the generator 3a is connected by conductors 54 and 56 to the manual control 35 potentiometer 50, or through the control switch 42 to the automatic control potentiometers 53. The electrical outputs from the respective generators, 29a and 3a, as controlled by the fields 29c and 3c are connected to the sighting target motor 40 29 and the rotary platform motor 3. Changes in the amplitude or potential of the current applied to the control fields 29c and 3c, of course, changes the amplitude and potential of the current in the fields 29d and 3d of the motors 29 and 3, thus 45 controlling the speed and direction of rotation of the sighting target advancing motor 29 and the rotary platform motor 3. The "amplidyne" control is well known and forms no part of the invention, and in fact, simple reversible motors 50 might be connected directly to the potentiometers indicated above if the inductances and resistances in the potentiometers were made sufficient to directly control the electric motor input currents. 55 Current is supplied to the control system at 40 and 60 41 from any suitable source.

During the manual control the two "manual-automatic" switches 42 and 43, respectively, controlling the platform and track motors, are moved 65 clockwise to positions 42a and 43a. Current from the source 40 and 41 passes through the terminal blocks 44, 45, 47 and 48, and the action switch 49 when closed, to the manually settable potentiometers 50 and 51 for the platform and sighting tar- 70 get control, the potentiometers being adjustable by the respective control knobs 35 and 34 on the front of the action control box at the instructor's station, as seen in Fig. 1. The two limit switches 11g and 11h are connected in the platform motor 75 circuit from the terminal block 48 and limit the

degree of azimuth deflection of the guns with respect to the scoring target.

Clockwise movement of the two switch devices 42 and 43 from their manual positions 42a and 43a to automatic control positions 42b and 43b, disconnects the circuits to the two manually operable potentiometers 50 and 51 and connects the conductors 52 and 53 to two groups of automatically operable potentiometers.

Referring to the face or front of the control panel at the instructor's control station D, legends have been applied to the various control elements. Under manual control when the sighting target and rotatable base control knobs 34 and 35 are in vertical position, as shown, and the "automatic" toggle switch is down, the two switch elements 42 and 43 in the wiring diagram are in the positions indicated at 42a and 43a, with the slider 52 and 53 of the potentiometers 50 and 51 in mid-position. The potentiometers have center taps from which conductors 54 and 55 lead to one operating terminal respectively of the control fields 3c and 29c for the platform rotating motor and the sight target motors 3 and 29. Conductors 56 and 57 connect the other terminal of each of the control fields 3c and 29c for the platform rotation and sight target moving motors 3 and 29 to the central or slider contacts 52 and 53 of the respective manual base and track control potentiometers. Manipulation of the control knobs adjusts the sliders 52 and 53 to vary the current potential delivered to the motors 3 and 29 through the conductors 54 and 55, and consequently varies the speeds of movements of the sighting target plane and the platform.

When the two switch elements 42 and 43 are moved to the automatic control position, as illustrated at 42b and 43b in Fig. 5, the circuits between the manually operable potentiometer sliders 52 and 53 and the motors 3 and 29 are interrupted and the conductor 56 is then connected to a conductor 56a, having a plurality of branches or conductors 56b, 56b, leading respectively to a series of automatically operable potentiometers 58, for the 90°, 45°, 22.5°, 11.25° and 0° angle simulated attacks. Each of these branch conductors has a control switch 59 therein as shown in Figs. 1 and 5 later to be described. These switches are normally open, and the closing of any of them connects the slider 60 of the selected attack angle control potentiometer 58 to the conductor 56a, which leads to the conductor 56 and to one terminal of the generator field 3c for controlling the motor 3 for rotating the platform 2. With respect to the switch element 43, seen in dotted line position 43b, effecting automatic control of the sighting target, the switch 43 now connects the conductor 57 from the sighting target motor 29 to the conductor 61 which also has a plurality of parallel branch conductors 61a leading to the slider contacts 62 of the sighting target controlling potentiometers 63 for the respective 90°, 45°, 22.5°, 11.25° and 0° simulated attacks. Each of the branch conductors 61a has a normally opened control switch 64 therein for interrupting the current between the potentiometer 63, connected to that branch, and the sighting target motor 29. Conductors 66 and 67 are connected to the power source 49 and 41, such as the plus and minus poles of a battery, or a generator (not shown), and lead respectively to the outside or end taps of the potentiometers 50 and 51, conductors 66a and 67a being connected respectively to the conductors 66 and 67, and lead to the current reversing switches 68 and 75.

These switches are simultaneously movable to connect the conductors 66a and 67a respectively with either the conductors 67b and 68b or the conductors 68b and 67b, for reversing the polarity to the terminals of the potentiometers 63 and 58.

A timer driving motor for actuating the respective slider contacts 60 and 62 of the potentiometers 58 and 63 is provided and also for closing the associated switches 59 and 64, later to be described. This timer motor is indicated at 70 in the wiring diagram of Fig. 5, current being supplied to the motor 70 through the conductors 66d and 67d. A switch 71 is interposed in the conductor 67d for interrupting the current to the motor 70 when this switch is open. The means for initiating the operation of the timer motor 70 is a manual circuit closing of the switch as indicated at 71.

Before describing my automatic timer, as best seen in Figs. 2, 3, and 4, it will be noted that the potentiometers 58 and 63 may be connected in the respective platform and sighting target motor controlling circuits by the closing of the associated control switches 59 or 64, and during the time the selected potentiometers are in the energizing circuit the positions of the respective slider contact arms with respect to the center taps determine the rate of rotation of the platform 2 and the rate of travel of the sighting target 32. Relative movements of the slider arms 60 and 62 also change the individual speed rates of the platform and sighting target during such movements.

Referring again to Figs. 2, 3 and 4 the timer motor 70 incorporates a reduction gear train (not shown) which drives a pinion 70a at a comparatively slow and constant speed. The drive pinion 70a meshes with a larger pinion 72 that is fixed on a timer shaft 73, suitably journaled in spaced brackets 74 and 75, as best seen in Fig. 2. The timer shaft 73 has a plurality of specially shaped cams 73a and 73b fixed thereon for actuating the sliders 60 and 62 of the potentiometers 58 and 63. A fixed supporting rod 76 is provided and secured at its ends in the brackets 74 and 75. This rod carries a plurality of levers 77 and 78 freely journaled thereon, each lever having a roller 79 which rides on the periphery of one of the cam discs 73a, 73b. The levers 77 as shown in Fig. 4 each carry an insulated switch contact plate 80, movable by its actuating cam member into contacting engagement with a fixed contact terminal 81. Leaf spring members 82 are secured to a fixed rod 83, as best seen in Fig. 4 for rocking the levers 77 and 78 clockwise to maintain the rollers 79 in contact with the periphery of the timer cams 73a and 73b as they rotate.

Referring to Figs. 2 to 4, the levers 78 each have a rack segment 78a fixed thereon, meshing with a pinion 84 fixed to one of the potentiometer slider arms 60 or 62 of the potentiometers 58 and 63, in the wiring diagram in Fig. 5. The timer motor 70 is of any conventional constant speed type that will cause rotation of the cam shaft 73 at a uniform speed, and the motor when started, should preferably rotate the shaft 73 a single revolution and then stop. The two switches may be connected in the motor operating circuit, under the control of the cams 73c and 73d so that one of the switches is open in a starting circuit, which circuit is closed by the starting switch 71 while the other cam controls a switch in the same circuit so that once the

starting switch 71 is closed, the cam 73c actuated by the timer shaft 73 closes the timer circuit and maintains the circuit closed until the cam discs rotate sufficiently for the configuration of the cam to again open the timer circuit and stop the timer. This complete cycle of operation occurs with respect to all of the potentiometers but, depending upon which of the platform and sight target potentiometer circuits are closed by the manual closing of the desired "type of attack angle" switches 59 and 64, only the potentiometers controlled by these switches are connected into the operating circuits which control the platform and sight target motors 3 and 29. The respective cam members 73a and 73b for operating the slider arms associated with the potentiometers which are switched into the circuit by the closing of the switches 59 and 64 determines the sighting problem. Since the contours of the cam members for the different potentiometer slider actuations are all formed differently, for the desired platform and sighting target motor operations, to each simulate one type of angle attack, such as 90°, 45°, etc., and that the respective connecting of these potentiometers in the circuit is by the selected pairs of switches 59 and 64, the closing of the left-hand switches 59 and 64 in the wiring diagram conditions the device for a subsequent 90° angle attack actuation. When the starting switch 71 is closed to start the timer, the potentiometer arms are all actuated by the timer cams 73a and 73b, but only the platform and sighting target potentiometers which were selected and connected in the control circuit by the manually selected attack angle switches 59 and 64 will be effective, causing the platform to be rotated and the sighting target to be moved toward the platform and turret, at definite predetermined ratios with respect to each other, as controlled by the predetermined contour of the selected platform and sighting target control cams.

The instructor's control panel discloses switches for simulating the attacks from angles of 90°, 45°, 22.5°, 11.25° and 0°. The wiring diagram only discloses two sets of these automatic potentiometer controls, namely, the 90° and 45° angle attack controls, the other attack angle potentiometers having been omitted from the drawing, since they are connected to the respective conductors 67b, 56a, 54, 68, 61 and 65a in identically the same manner as the potentiometers 58 and 63 as shown in the drawings. Likewise in the fragmentary views of the timer mechanism, Figs. 2 to 4, there are only two sets of potentiometers and control cams disclosed, the contour of which controls the platform and sight target motors for the two different attack angles. In order to provide controls for the other angles indicated, three additional sets of control cams, not shown, are provided.

In the operation, referring to Fig. 1, the sighting target 32 is disposed on the remote end of the track frame farthest away from the gunner in the turret 7 who is to "sight" his guns on the sighting target 32. The instructor at his control station now selects the problem to be presented to the gunner. For instance, if a 90° approach attack is selected, the 90° attack angle switch is closed connecting the two slider arms of the two potentiometers, farthest to the left (in Fig. 5) of the potentiometer groups 68 and 63, to the controlling circuits of the respective sighting target and platform motors, so that these circuits are conditioned for operation. To

start the automatic cycle the instructor now closes the "action" or starting switch 71, closing the circuit to the timer motor 70. Operation of this motor rotates the timer shaft 73 and the cams 73a, 73b, 73c and 73d fixed thereon, actuating the respective levers 77 and 78. Movement of the levers 77 operates the switches 80 in the desired order, and, as the timer continues to operate, the controlling circuits for the respective platform and sighting target motors are energized. As the cams 73a and 73b are rotated, the potentiometer sliders are shifted from the center tap position toward the end taps at a predetermined rate, but not necessarily a constant rate since this depends upon the contour of the associated cams for the controlling potentiometers, as selected by the energizing switches 59 and 64. The movement of the slider 60 of the selected potentiometer 58 causes the platform to be rotated at a predetermined rate, while the movement of the selected potentiometer sliders 62 controls the rate of movement of the sighting target plane from the outer end of the track toward the gunner.

The combined movement of the platform and sighting target, when the sighting target is viewed by a gunner through his gun sights, simulates a definite pursuit curve being flown by the attacking plane toward a bomber carrying the gunner.

While the construction shown and described accomplishes the objects of the invention as herein stated, this disclosure is not intended to confine the invention to the specific embodiment illustrated as various modifications may be made without departing from the spirit of the invention as set forth in the following claims.

I claim:

1. In an aircraft gunnery practice range having a stationary scoring target, a support, a platform rotatable on the support on a substantially vertical axis, a turret mounted on the platform for independent rotation, guns carried by the turret having a sighting means therefor with a sighting axis elevated above the line of fire of the guns and directable incident to rotation of the turret and the elevation or depression of the guns, a sighting target airplane movable in a substantially vertical plane toward the rotary axis of the platform during rotation thereof, whereby relative predetermined different rates of rotative displacement of the sighting axis incident to predetermined different rates of rotative displacement of the platform, and predetermined different rates of movement of the sighting target airplane toward the sighting means from an initial position remote from the rotary axis of the platform, simulates a pursuit plane flying toward the sighting means on different predetermined pursuit curves, simulating a bomber in flight when attacked by the pursuit plane, and relatively separate power means connected to the platform for independently rotating the platform and connected to the sighting target airplane moving the sighting target airplane toward said platform axis, in the target sighting axis, when the line of fire of the guns are trained on the scoring target; the improvement which includes an improved control device comprising a first group of independent speed control devices, each selectively and independently connectable with the power means for rotating the platform at a predetermined different rate, a second group of independent speed control devices, each of which is selectively and independently connectable with the power means

for moving the sighting target at a predetermined different rate toward the platform axis, and manually controllable selector means operable to simultaneously connect predetermined pairs of said independent speed control devices one from said first group and one from the second group respectively to the platform and sighting target moving power means, for rotating the platform and moving the sighting target simultaneously, at predetermined different definite ratios, for simulating definite predetermined pursuit curves flown by a pursuit plane attacking the bomber from different definite angles when the sighting target is viewed from the platform through the sighting means.

2. In a gunnery trainer device, the combination with a fixed support, a platform rotatable thereon about a fixed axis, a directable gun unit mounted on the platform having gun sighting means therefor with its sighting axis adjusted in elevation above the line of fire of the gun unit, a scoring target fixed at a remote point with respect to the rotary axis of the platform, a movable sighting target disposed to travel from a different remote point toward the platform axis in line with the gun sighting axis of the gun sighting means when the line of fire of the guns are trained on the scoring target, regulatable power means for rotating the platform about its axis with respect to the movement of the sighting target toward the platform axis, regulatable power means for moving the sighting target from said different remote point toward the platform at different rate during rotation of the platform; a unitary control device for simultaneously controlling the rate of rotation of the platform and the rate of movement of the sighting target toward the platform, said unitary control device comprising a first group of independent power control devices each selectively connectable with the platform rotating power means, to rotate the platform about its axis at a predetermined definite different speed, and a second group of independent power control devices each selectively connectable with said sighting target advancing power means to move the sighting target toward the platform from the different remote point at a predetermined definite different speed, and manually operable selector means movable to connect predetermined pairs of said power control devices, one from each group, to the respective platform rotating and sighting target advancing power means, for rotating the platform about its axis and moving the sighting target toward the platform axis at a plurality of definite predetermined rates with respect to each other.

3. In a gunnery trainer device having a support, a platform rotatable thereon about a vertical axis, a directable gun unit mounted on the platform for independent rotation about said axis having sighting means therefor with its sighting axis adjusted to a predetermined elevation relative to the line of fire of the gun unit, a scoring target fixed with respect to the rotary axis of the platform at a remote point therefrom, a movable sighting target disposed to travel from a different remote point toward the platform axis in the sighting axis of the gun sighting means when the line of fire of the gun unit is trained on the scoring target, adjustable power means for rotating the platform at different rates with respect to the movement of the sighting target toward the platform, power means for moving the sighting target toward

the platform at different rates during rotation of the platform; the improvement comprising a control device for selectively controlling the rate of rotation of the platform relative to the rate of movement of the sighting target toward the platform comprising a motor driven timer device having a uniformly driven cam shaft, a plurality of control cams fixed on said shaft, each cam having a different predetermined contour, a plurality of actuating levers pivotally positioned adjacent said cams each lever disposed in actuating engagement with one of said cams, individual variable power control means for controlling the rate of rotation of the platform and the rate of movement of the sighting target and operable by each of said levers and selectively connectable with the platform rotating and sighting target moving power means to selectively rotate the platform and move the sighting target towards the platform at definite predetermined different rates of movement.

4. In a gunnery trainer device having a support, a platform rotatable thereon about a vertical axis, a directable gun unit mounted on the platform for independent movement having sighting means with its sighting axis adjusted in elevation to a predetermined degree relative to the line of fire of the gun unit, a scoring target fixed at a remote point with respect to the rotary axis of the platform, a movable sighting target disposed to travel from a different remote point toward the platform in the sighting axis of the gun sighting means when the line of fire of the gun unit is trained on the scoring target, electrically operable power means for rotating the platform with respect to the direction of movement of the sighting target, electrically operable power means for advancing the sighting target toward the platform during the rotation of the platform, including separate energizing circuits for the platform rotating means and the sighting target moving power means; a power driven timer device for variably energizing said energizing circuits comprising a first group of potentiometers selectively connectable in the energizing circuit for the platform rotating electrical power means to rotate the platform at different rates, a second group of potentiometers selectively connectable in said energizing circuit for the sighting target moving power means for advancing the sighting target toward the platform at different rates, an electrically operable motor driven cam shaft having a plurality of cams fixed thereon, one for each potentiometer, actuating means between each cam and a potentiometer including an operating connection for operating the potentiometer to control the electrical potentiometer in its associated energizing circuit in a predetermined ratio to the contour of the operating cam for that potentiometer, manually selectable switch means in each platform rotating power energizing circuit, manually selectable switch means in each sighting target moving power energizing circuit for closing the circuits selectively, whereby the operation of selected pairs of the switch means connect predetermined potentiometers in the platform rotating control circuit and in the sighting target moving control circuit for rotating the platform about its axis and moving the sighting target toward the platform from the said different remote point at predetermined definite ratios with respect to each other, and energizing circuit for operating the cam shaft motor, and switch means in said last energizing circuit for closing the circuit and initiating the oper-

ation of the timer while the selected potentiometers are connected in the associated platform rotating and sighting target moving electrical energizing circuits.

5. In an aircraft gunnery practice range comprising a relatively fixed support, a power driven platform rotatable on a vertical axis on the fixed support, an aircraft gun turret independently rotatable about said vertical axis on the platform, a miniature sighting target airplane movable from a remote point toward the vertical axis of the platform during rotation thereof for simulating a pursuit plane flying a pursuit curve when attacking a bomber, when the sighting target airplane is observed from within the turret while the platform is rotating, the bomber being simulated by the platform and turret thereon and the pursuit plane being simulated by the sighting target airplane, a gunnery instructor's control station remote from the platform and the sighting target for controlling the relative movements of the platform and sighting target airplane; the improvement which comprises a plurality of separate groups of speed control devices the devices of one group being selectively connectable to the platform power rotating means for rotating the platform at definite different rates and the other group to the sighting target moving means, each control device in the first group selectively determining the rate of rotating the platform at a definite different predetermined speed and each control device in the second group determining the rate of movement of the sighting target toward the turret axis at a selectively different predetermined definite speed, and manual selector means at said instructor's control station for selectively connecting predetermined pairs of said separate speed control devices one from each group to the platform and sighting target power means to selectively rotate the platform and move the sighting target toward the platform axis at definite predetermined rates with respect to each other.

6. In a gunnery trainer device, the combination with a support, a platform rotatable thereon about a fixed axis, a directable gun unit mounted on the platform having sighting means therefor with its sighting axis adjusted in elevation relative to the line of fire from the gun unit, a stationary scoring target fixed with respect to the platform axis at a remote point, a movable sighting target disposed to travel from a different remote point toward the platform axis in the sighting axis of the gun sighting means when the line of fire of the guns is trained on the scoring target, regulatable platform rotating power means for rotating the platform at different rates with respect to the position of the sighting target, regulatable sighting target advancing power means operatively con-

nected to the sighting target for moving the sighting target from said different remote point toward the platform at different rates during rotation of the platform; a control device for simultaneously determining the rate and direction of rotation of the platform and the rate of movement of the sighting target toward the platform axis, said control device comprising an operation timer having a uniformly driven timer shaft, a first group of independently adjustable power control elements simultaneously driven by said timer shaft and selectively connectable to the platform rotating power means, and a second group of independently adjustable control elements simultaneously driven by said timer shaft and selectively connectable to the sighting target advancing power means for actuation thereof, control means movable to selectively connect any one of the adjustable power control elements of the first group to the power means for rotating the platform at predetermined different rates and connect any one of the adjustable power control elements of the second group with the sighting target advancing power means for advancing the sighting target toward the platform at predetermined different rates, actuated by the timer shaft to combine rotation of the platform about its axis and movement of the sighting target from the said different remote point toward the platform at predetermined definite relatively different predetermined rates, for simulating the appearance of predetermined attacks of a pursuit plane on a bomber from definite predetermined different angles relative to the flight axis of the bomber when the sighting target is observed through the sighting means during simultaneous rotation of the platform and movement of the sighting target toward the platform axis at the said predetermined different rates.
